UNITED STATES PATENT OFFICE.

MATTHIAS BROCK, OF BOSTON, MASSACHUSETTS, ASSIGNOR TO UNITED SHOE MACHINERY CORPORATION, OF PATERSON, NEW JERSEY, A CORPORATION OF NEW JERSEY.

UPPER-SHAPING MACHINE.

1,414,498.

Specification of Letters Patent.

Patented May 2, 1922.

Application filed May 4, 1918. Serial No. 232,525.

To all whom it may concern:

Be it known that I, MATTHIAS BROCK, a citizen of the United States, residing at Boston, in the county of Suffolk and State of Massachusetts, have invented certain Improvements in Upper-Shaping Machines, of which the following description, in connection with the accompanying drawings, is a specification, like reference characters on the drawings indicating like parts in the several figures.

This invention relates to upper shaping machines and is herein shown as embodied in a machine adapted, among other uses, for forming uppers as a preliminary operation to the operations of pulling-over and lasting, or preliminary to lasting in case the pulling operation, as such, is omitted.

An object of the invention is to provide a machine which will so effectively stretch and shape an upper at its toe portion that the work of pulling-over the upper will be greatly facilitated and that the lasting operation may be more expeditiously and effectively performed, particularly when the upper stock is of heavy and resistant leather or other material.

A further object of the invention is to provide a machine which, under favorable conditions, will so stretch and form the upper at the toe end that the pulling-over operation may be dispensed with and the upper may be lasted by an automatic or other toe lasting machine, or by the use of which the upper may be so formed as to require no further shaping over the toe.

In machines of this type as frequently constructed, the inside former, about which the upper is shaped, normally projects above the plane in which the margin is to be confined and the upper, in being presented between the confining means, has its body portion raised by the former relatively to the marginal portions before it is clamped, this effect being known as "humping" the vamp or upper. If, with the work in this position, an attempt is made to seize the upper by relative movement of the confining members, the upper may be foreshortened, that is, may draw back somewhat out of the confining means before it is clamped.

A feature of this invention consists in

means for preventing the drawing back of the upper at the toe end and as shown herein comprises a member yieldingly upheld above the face of one of the confining members in position to engage the end of the upper and force it against the face of the other confining member at the beginning of the operation of the machine so that the upper will be held from withdrawing longitudinally from the confining means during the movement thereof to confine the upper margin and the upper will be caused to be brought into humped position over the former. Further, this member will, by relative movement between it and the former, effect a preliminary pulling of the upper longitudinally to effect lengthwise stretching of the upper as the former and confining means move relatively. As shown herein, the yielding means for holding the upper at the toe end is compressible to permit the upper engaging face to assume a position flush with the face of the lower confining member and to form a part of it during subsequent forming operations. Preferably, a plurality of means for engaging and holding the upper at the end of the toe is provided, which means may engage the upper at first simultaneously and then yield up the stock successively as the forming operation proceeds. This means may comprise, as shown, yielding sections of the upper confining means with means for distributing and equalizing the holding pressure between them. The upper engaging faces of the sections are differently formed, for example, one with ribs and another with teeth, and more holding pressure may, as in the construction shown, be applied to one of the sections, for example, the toothed section, than to the other. The result of this arrangement is to effect a strong preliminary pull lengthwise of the upper when it is engaged by both of the sections and a lesser pull after the upper has been withdrawn from one of them. Preferably, a rigid portion of the confining means, for example, a rib, is arranged between the sections to effect, during the later stages of the operation, a more positive confinement of the upper.

Another feature of the invention consists in means arranged to act, after the prelimi-

nary longitudinal stretching of the upper is effected and before general confinement of the upper about the whole toe takes place, to tension the upper radially of the toe curve, 5 for example, at a corner of the toe. Preferably, one of these corner stretching means is located at each corner of the toe, and each is arranged to yield into the confining means to allow a portion of the confining means, for 10 example, a rib thereon between said means and the former, to come into engagement with the upper at that point. Furthermore, the corner stretching means co-operate with the confining means to effect a more secure 15 holding of the upper at the corners of the toe to cause a greater stretching effect to be secured at the corners than at other portions of the upper margin.

Another feature of the invention consists 20 in a plurality of ribs arranged on the confining means in substantially parallel relation to the sides of the former, the ribs being more numerous about the toe end of the confining means. Preferably, the ribs have 25 rigid sections interspersed with yielding sections and the rigid section of one rib is arranged to overlap or break joints with the yielding section of another rib so that, in the final action of the confining means, the 30 upper is held at all points about the upper at the toe by a rigid rib. As shown herein, there are three ribs, the intermediate rib being shorter than the other two and located about the end of the toe to obtain a greater 35 holding effect upon the upper about the toe end than at other parts of the toe.

Another feature of the invention consists 40 in means on the confining means for distributing the upper fullness and determining the location of the folds in the upper in its passage through the confining means. As shown, this means may comprise radial ribs on one of the confining means located so as to be engaged by the toe end of the 45 upper.

Another feature of the invention consists 50 in means for controlling the movement of the upper in the direction of the tip line and for feeding it toward the former during the upper forming operation. Means may advantageously be combined with said controlling means for advancing portions of the upper at the end of the tip seam toward the 55 end of the toe of the former and relatively thereto. As shown herein, grippers are arranged to be closed by operation of the confining means and are operated by relative movement of the confining means and the former to feed the stock at the tip seam laterally of the former and obliquely toward the toe of the former. Preferably, the jaws 60 of the grippers which engage the outside of the upper leather are toothed and the jaws which engage the lining, if any, are relatively smooth so that during the forming 65

operation the upper leather at the tip line will be held more firmly than the lining, and the lining may readily slip from the jaws when sufficient tension has been applied thereto, the upper leather at the same time 70 being held by the toothed jaws and more strongly tensioned before slippage is permitted.

Another feature of the invention consists 75 in improved means for applying pressure to the top of the upper to hold it against displacement relatively to the former and prevent, for example, bowing of the tip seam. As herein shown, this means applies a powerful pressure yieldingly to the upper on the 80 former over a substantial area of the toe including the tip seam and excluding the high part of the toe, and connections are provided for allowing the pressing means to move with the former, said connections operating at a different rate than the former 85 so that the holding pressure on the upper is controlled and may, for instance, be caused to increase as the forming operation proceeds. Preferably automatic means is provided for causing release of the pressing means at the end of the forming operation and for moving it out of the way, the pressing means remaining in inoperative position until manually moved into operative position for the next operation of the machine.

Another feature of the invention consists 90 in improved means for pressing or wiping the upper against the end and sides of the former during the forming operation. As 95 shown herein, the pressing means comprises parts pivoted together and having faces contoured to fit the end and sides of the former. The machine is organized to advance the pressing means yieldingly against the 100 end of the toe and to apply, by closing movement of the parts, pressure against the sides of the toe. Furthermore, the means for closing the parts is yielding and continuously acting and is independent of the means 105 for advancing the pressing means against the end of the toe. During the advancing movement of the pressing means toward the former, the upper is treated by the said means to an ironing action directed toward the rear of the former. Furthermore, during the relative movement of the pressing means and the former perpendicular to the bottom of the former, the upper is wiped 110 or ironed heightwise of the former in a direction toward the bottom of the former, and when relative movement ceases temporarily, the upper is held clamped to the former, even though withdrawn from the 115 confining means, to hold the upper in tensioned condition for a period to allow the upper to set in the shape into which it has been formed.

These and other features of the invention 120 will appear more fully from the following 125 130

detailed description when read in connection with the accompanying drawings and will be pointed out in the appended claims.

In the drawings,

5 Fig. 1 is a side elevation of the machine, certain parts being shown in section;

Fig. 2 is a sectional plan view showing the arrangement of the cams from which the operative movements of the machine are 10 derived;

Fig. 3 is a side view of the upper portion of the machine on an enlarged scale, parts being broken away better to show the upper forming mechanism;

15 Fig. 4 is a detailed perspective view of the top portion of the upper confining means;

Fig. 5 is a plan view of the lower portion of the upper confining means;

20 Fig. 6 is a front view of a portion of the machine;

Fig. 7 is a detailed sectional view of the parts shown in Fig. 5; and

Fig. 8 is a perspective view of the former.

25 In the drawings, the numeral 2 indicates the lower part of the frame of the machine, and the numeral 3 the upper part which is rigidly secured to the lower part. In the frame 2 are journaled three shafts, 4, 30 5 and 6. On the shaft 4 is a driving pulley 8 to which power is applied to drive the machine. The shaft 4 carries a pinion engaging a large gear on the shaft 5 which in turn has a pinion meshing with a gear 35 12 on the shaft 6. While the reducing gear between the shaft 4 and the shaft 6 is not fully shown in the drawings, its arrangement and purpose will be readily understood. As shown in Fig. 2, the machine

40 is duplex—two distinct upper forming mechanisms being operated from the shaft 6 and the operating parts of these mechanisms being symmetrically arranged with respect to the central gear 12. The parts 45 shown at the left of Fig. 2 will be particularly described with reference to the mechanisms shown in other views for operating upon an upper intended for the left foot, it being understood that the mechanisms

50 upon the right side of the machine are similarly and symmetrically designed and arranged for forming an upper for the right foot. Upon the left hand portion of the shaft 6 is a sleeve 14 to which are fixed several cams to be referred to for operating various parts of the machine. Clutch mechanism of any suitable construction is provided between the gear 12 and the sleeve 14 for causing rotation of the sleeve, the

55 operating cycle of which preferably takes place in two steps under the control of a treadle 16, the right hand side of the machine being independently controlled by a similar treadle.

60 At the front of the machine (Fig. 1) is

a vertical post 20 arranged for longitudinal reciprocation by a lever 22 pivoted at its rear end upon a shaft 24 and having between its ends a roll 26 engaging a path in a cam block 28 mounted on the sleeve 14. Means is provided for adjusting the length of the post 20, which means comprises a sleeve 27 rotatably mounted on the lower portion of the post and having threaded engagement with its upper portion. By 75 turning the sleeve 27 the length of the post 20 may be varied, the adjustment being maintained by a set nut 29. The upper end of the post 20 carries an inside former 30 having the shape of the forepart of a left shoe, as shown in Fig. 8. In this former 30, the characteristics of the last for which the upper is to be formed may be exaggerated, for instance, the height of the toe 80 may be increased so as to over-mold an upper and cause it to fit more readily a last having a toe of less height than the former.

Embracing the post 20 and arranged for movement in the same direction, is a slide 90 32, upon the upper end of which the lower part of the means for clamping or confining the margin of the upper is mounted. The slide 32 has a rearward projection 34 through which extends loosely a stud 35 95 pivoted to the forward end of a lever 36. The lever 36 is fulcrumed on the shaft 24 and has between its ends a roll engaging a path in a cam block 38 fixed on the sleeve 14 (Fig. 2). On the stud 35, between a shoulder on the stud and the projection 34, is a spring 40 through which upward movement is communicated yieldingly from the lever 36 to the slide 32.

The slide 32 has an inclined upper face 105 (Fig. 3) provided with upstanding ears, 46, 48 at its ends, through which are threaded screws 50, 52 having conical ends which engage suitably formed recesses in a block 54 to permit tipping of the block about an axis 110 extending lengthwise of the former 30. Set nuts 53, 53 are provided to hold the screws 50, 52 in adjusted position. By loosening the set nuts and turning both of the screws 50, 52, the block 54 may be adjusted lengthwise of the form.

Over the block 54 is arranged the lower member 56 of the vamp or upper confining or clamping means, of which Fig. 5 is a plan view. The block 54 has upstanding ears 58 at its sides which receive 120 trunnions 60 on the member 56, which trunnions provide a transverse axis about which the member 56 may tip. The trunnions 60 and cone bearings 50, 52 provide two axes 125 at right angles to each other about which the lower member 56 of the upper clamping means may adjust itself to equalize the upper confining pressure applied by forcing the member 56 upwardly against upper confining jaws 64, 66 arranged above it and later 130

to be described. The member 56 has a notch or opening of the shape of the former 30 (Fig. 5). The upper face of the member 56 may, as shown, have a separate upper 5 confining or clamping plate 57 inserted therein and held by pins 59, the plate 57 being formed with upper gripping and ironing ribs arranged substantially parallel with the inner edge of the member 56 and comprising 10 a rib 70 close to the edge of the member 56, a rib 72 spaced farther from the rib 70 about the point of the toe than at the sides of the toe, and an intermediate rib 74 shorter than the other ribs and located between 15 them about the end of the toe. If desired, of course, the plate 57 and the ribs described may be formed integrally with the member 56.

To effect a preliminary drafting of the upper longitudinally, sections of the ribs 70, 74 at the end of the toe are formed on a separate piece 76 inserted in a dove-tail slot in the plate 57 and member 56 and upheld from beneath by a spring 78 (Fig. 7) which acts 20 against a plate 80 on which the piece 76 rests. The formation of the piece 76 and its slot is such that movement of the piece toward the former 30 is prevented. Still 25 farther from the end of the toe is another inserted piece 82 having a toothed or roughened upper engaging face and arranged also to rest on the plate 80. The plate 80 can rock with relation to the spring 78 and equalize pressure on the inserted pieces 76, 30 82, and, in case the upper is too short to engage both of the pieces 76, 82 or after the upper has slipped from engagement with the piece 82, the spring 78 will still hold the piece 76 against the upper. The spring 78 35 may be arranged, as shown in Fig. 7, more nearly under the piece 82 so that greater holding effect will be secured by the piece 82 than by the piece 76. The pieces 76, 82 normally extend a substantial distance above 40 the face of the plate 57 so that they engage the upper and apply thereto longitudinal tension before the upper is engaged elsewhere about the toe, and by further movement of the member 56 toward the members 50 64, 66, are depressed against the spring 78 to permit the rib 72 and other portions of the ribs 70, 74 to engage the upper.

At each of the corners of the toe is a spring plug 84 which has formed upon it portions 55 of the ribs 72, 74. These plugs are normally raised by suitable springs so that their upper faces extend above the plate 57 but in a plane slightly below the plane of the faces of the pieces 76, 82. The plugs 84 engage the upper 60 at the corners of the toe after the upper has been drafted longitudinally by the action of the pieces 76, 82 and act to effect preliminary drafting of the upper radially at the corners of the toe before they are depressed to allow other portions of the upper 65

confining ribs 72, 74 and the ribs 70 to come into holding engagement with the upper. It will be seen that, by this construction, the rigid portions of the ribs "break joints" so that at all points about the toe there is some portion of a rigid rib to engage the upper when the clamping or confining of the upper is completely effected. At each side of the clamping piece 82 and between it and the spring plugs 84 are arranged radial ribs 86 70 75 which act upon the upper to determine the number and location of the folds in the upper as it is drawn through the confining means and to distribute the fullness of the upper about the end of the toe. These ribs also 80 assist the ribs 70, 72, and 74 in eliminating the wrinkles in the upper as the upper is drawn through them in the operation of the machine, as will be better understood after the construction of the machine has been 85 fully described.

The means for confining the upper comprises the parts carried by the member 56 already described and the co-operating confining jaws 64, 66 above referred to, which 90 will now be fully described with reference to Figs. 3 and 4.

Mounted in guides in the upper portion 3 of the frame is a slide 90 arranged for movement longitudinally of the former 30 95 and parallel to the upper face of the plate 57. The slide 90 has a U-shaped notch through which the former 30 may pass in its upward movement. On the lower face of the slide 90 is secured a bracket 94 (Fig. 4) 100 which supports a pivot 96 about which members 97, 98, which carry the confining means 64, 66, may turn. The forward ends of the members 97, 98 are provided with T-head 105 projections which engage T-head guides 100 105 formed in the slide 90 about the pivot 96 as a center. The confining means 64, 66 are also mounted on the pivot 96 and are adjustably held to the members 97, 98 by cap screws 102 arranged in countersunk slots 110 in the parts 64, 66. This construction enables the parts 64, 66 to be opened or closed relatively to the members 97, 98 for adjustment to accommodate different sizes of forms. The members 97, 98 are held toward 115 each other by leaf springs 104 secured at 106 to levers 108, 110 pivoted at 112, 114 to the ends of a T-head 116 operated by a rod 118. The rear ends of the levers 108, 110 carry 120 screws 120, 122, the heads of which engage 120 the ends of an abutment piece 124 secured to the head 116. An upstanding projection 126 on the T-head is secured to the slide 90 and when the rod 118 is moved longitudinally 125 by means to be described, the slide 90 is moved toward the former 30, the leaf springs 104, 104 acting yieldingly to hold the contoured edge faces 65, 67 of the confining means 64, 66 toward the former in embracing relation thereto. Pressure of the 130

faces 65, 67 against the former may be varied by adjusting the screws 120, 122. The contoured faces 65, 67 press the upper against the former 30, act to wipe the 5 upper heightwise of the former, form ironing means during the movement of the upper across them, and finally act as means for holding the upper against the former under tension after the upper is withdrawn 10 from between the flat confining faces of the members 64, 66 and the co-operating means on the plate 57. The rod 118 is actuated by a bell crank lever pivoted at 130 (Fig. 3), the vertical arm 132 15 of which has a pin and slot connection 134 to the rod 118 and the arm 136 of which is connected by an operating rod 138 to an arm 140 (Fig. 1) of a lever pivoted on the rod 24 to the frame 2 and having an arm 144 20 which carries a roll engaging a path in the cam block 146 fixed on the sleeve 14. To afford yielding connection between the rod 138 and the arm 140, a sleeve 145 is provided which is loose on the rod 138 and carries a 25 pin journaled in the lever 140. Between the sleeve 145 and a nut 147 on the end of the rod is a spring 148 through which the arm 140 acts to effect a yielding downward pull on the rod 138. A nut 149 on the rod 138 above 30 the collar 145 causes return movement of the arm 140 to be communicated positively to the rod 138, and the nuts 149, 147 afford means for adjusting the rod relatively to the arm 140 and for maintaining the spring 35 148 under any desired degree of tension. The cam 146 effects, through the spring 148, at the proper time in the cycle of operation of the machine, a forward movement of the slide 90 and causes the contoured faces 65, 40 67 of the members 64, 66 to be pressed against the toe end of the former with a pressure determined by the tension and adjustment of the spring 148. The pressure of the faces 65, 67 against the sides of the 45 former is independently and adjustably determined by the leaf springs 104, 104 and the screws 120, 122, and since these faces are yieldingly held toward each other continuously by the springs 104, 104, the faces 65, 50 67 effect a wiping or ironing of the upper lengthwise of the former as they are advanced into pressing relation to the end of the former. This pressing action of the faces 65, 67 occurs before the movement of 55 the former 30 is completed and hence the faces 65, 67 act to wipe or iron the upper in a direction heightwise of the former toward the bottom of the former.

Means is provided for seizing the upper 60 at the ends of the tip seam and for feeding it laterally of the former 30 and obliquely toward the toe of the former during the upper forming operation. This means comprises grippers (Fig. 6) located at each 65 side of the toe and having upper and lower

jaws 150, 152 respectively. The jaws 152 are arranged to slide in oblique T-guides 154 formed in the upper face of the member 56. The upper jaws are pivoted at 156 to the lower jaws and springs 158 are connected between pins 160 on the jaws and pins 163 on the block 54 to open the jaws. The upper jaws 150 enter recesses 162 in the confining means 64, 66 and plungers 166 (Fig. 4) operated by springs 167 (Fig. 3) 70 mounted in the slide 90 and arranged to engage the upper jaws 150 and force them yieldingly into engagement with the upper when the upper confining means are brought together. Preferably the upper jaws 150 75 are provided with teeth and the lower jaws are preferably smooth, as shown in Fig. 6, to afford a firm grip upon the upper and a less firm grip upon the lining, in case a lined upper is being treated. To move 80 the grippers toward each other in the guideways 154, two levers 170, 172 are provided which are pivoted between their ends at 174 and 176 respectively to a part 33 secured at 85 37 to the slide 32. The lower ends of the levers have slots, the lower parts 173 of which are upwardly and inwardly inclined, and the upper parts 177 of which are parallel after the full movement of the levers has been effected by the upward movement 90 of pins 178, 178 which project forwardly through the slots from a member 175 secured by a set screw 179 to the plunger 20 that carries the former 30. Slots 180 in the upper ends of the levers 170, 172 are engaged by extensions of the pivot pins 156 of the upper jaws 150. When the plunger 20 is raised, the pins 178, 178 act on the inclined portions 173 of the slots in the levers 170, 172 to cause approaching movement 105 of the upper ends of the levers and hence movement of the grippers toward each other laterally of the shoe toe and also, because of the inclined direction of the T-guideways 154, movement toward the end of the toe. 110 Previously, of course, the grippers have been closed by being pressed upwardly against the spring plungers 166. The grippers prevent shifting of the stock transversely of the former 30 and feed it at the proper rate 115 during the action of the former while maintaining proper tension on the stock in the direction of the tip line. At the same time the inclination of the guides 154 causes the ends of the tip seam or tip line to be moved 120 toward the toe of the former to maintain the tip line in proper transverse relation to the former during the upper forming operation.

To further control the stock adjacent to 125 the tip seam, a compression member 182 (Fig. 3) is provided which co-operates with the former 30 and the grippers. The compression member 182 is angular in shape and has a face 183 for engaging the toe of the 130

upper locally over the tip line, which face may be covered with leather or other suitable material. At its inner end, the member 182 is pivoted at 184 to a plunger 186 mounted for vertical movement in the frame 3. Fixed to the plunger 186 is an arm 187, between the end of which and the angle of the member 182 is connected a toggle 188, 189. On the central pivot of the toggle is a roll 190 which co-operates with a cam 192, fixed to the frame 3, in a manner and for a purpose which will later appear. The plunger 186 is operated by means comprising an angle lever pivoted to the frame 3 at 196. One arm 197 of the lever has a pin and slot connection with the plunger 186 (Fig. 3), the other arm 198 of the lever being connected by a link 200 to an upstanding arm 201 of an angle lever pivoted at 130 to the frame 3 and having its other arm 202 connected to a rod 204. The lower end of the rod (Fig. 1) has a yielding connection with an arm 206 of its operating lever, which connection comprises a sleeve 210 loose on the rod 204 having pins engaging holes or notches in the bifurcated end of the arm 206. Between the sleeve 210 and a nut 212 on the arm 204 is a spring 214 which may be held under any desired degree of tension by a nut 216 on the rod 204. A downwardly projecting arm 208 of the operating lever 206 has a roll engaging an edge cam on the cam block 38.

Referring to Fig. 8, it will be seen that the former 30 is provided with a plate 31 having teeth arranged to project above the surface of the former at its rear end. In case the operator is treating particularly refractory uppers which show a tendency to slip toward the toe, he may, by holding the work against the teeth on the plate 31, obtain a grip on the upper which will prevent its being drawn forward. The plate 31 may, of course, under proper conditions, be used instead of the compression member 182.

The operation of the machine is as follows:

The parts being in the position shown in Figs. 1 and 3, the operator places an upper between the upper confining means on the plate 57 and the confining means 64, 66 and the portion of the upper at the tip line between the jaws 150, 152 of the grippers which are open and separated as shown in Fig. 6. He then straightens the toggle 188, 189, causing the compression member 182 to be depressed into position to engage the former when the former is raised. When straightened, the center of the toggle passes slightly beyond the position of alignment with its end pivots so that it forms a rigid support for the compression member 182 against upward movement, except as such movement is permitted by movement of the plunger 186. He then depresses

the treadle 16 which effects a connection between the continuously driven gear 12 and the sleeve 14 carrying the cams by which the left hand side of the machine is operated. At first the post 20 and the slide 32 rise together causing the portion of the upper adjacent to the tip seam to be pressed against the member 182 and the yieldingly upheld pieces 76, 82 at the end of the toe to clamp the upper against the flat lower face of the members 64, 66. By this movement of the former 30 against the member 182, the spring 214 may be somewhat compressed to hold the upper from slipping forwardly at the tip line. The former 30 now begins to rise relatively to the slide 32, the slide 32 continuing to rise at a lower rate. The initial position of the former 30 is such that the upper, in being placed over the former and brought at its periphery between the confining means and between the grippers, is humped over the former and the relative movement of the former and the toe end gripping members 76, 82 causes the upper to be brought down over the toe end of the former before the margin is elsewhere confined. In this operation, folds of fullness may occur adjacent to the radial ribs, which ribs act to distribute this fullness and co-operate with the confining means to eliminate it as the operation proceeds. This relative movement also causes the upper to be stretched longitudinally because of the holding action of the pieces 76, 82, and when a little later the spring plugs 84 engage the upper at the corners of the toe, the fullness, caused by bending the upper over the former, is prevented from extending beyond the plugs 84, and the upper is tensioned radially at the toe end.

Meantime, the spring plungers 166 have closed the grippers upon the upper at the tip line and the grippers have been caused to move toward each other by the relative movement of the post 20 and the slide 32. As the former 30 moves upwardly, the compression member 182 is allowed by its cam to rise with the former at a lower rate, the tension of the spring 214 gradually increasing as the operation proceeds to hold the upper against the former with increased force. Thus all danger of bowing of the tip seam because of slippage of the upper toward the toe is avoided.

After the slide 32 has been raised sufficiently to cause the depression of the pieces 76, 82 and the plugs 84, the upper is confined by the ribs 70, 72, 74 about the periphery of the toe portion, and after this movement of the former 30 is continued gradually to draw the upper from between the upper confining means. Meantime and while the upper is still held by the confining means, the slide 90 is moved toward the shoe by

the operative connections to the rod 118 as described, and the spring 148 in said operative connections together with the leaf springs 104 causes the parts 64, 66 to 5 be held with their faces 65, 67 against the end and sides of the former while the upper is still under tension and act first to rub or iron the upper rearwardly at the sides of the toe, then, as movement of the former 10 continues, to wipe, rub or iron the upper at the end and sides of the toe heightwise toward the bottom of the former. When the lower or sole face of the former has reached substantially the plane of the lower face 15 of the members 64, 66, the machine stops to allow the upper to set in the shape it has been made to assume. At this time, the margin of the upper may or may not have been completely withdrawn from between 20 the upper confining means, depending on the size and shape of the upper, but the upper is held clamped tightly to the former 30 by the contoured faces 65, 67 of the parts 64, 66 and by the grippers 150, 152. After 25 an upper for the right foot has been similarly treated in the right hand side of the machine, the operator again steps on the treadle 16, and thereupon the slide 32 is dropped slightly to release holding pressure 30 on the margin of the upper if it is still between the confining means, and the movement of the former and of the compressor 182 is continued to iron the upper against the contoured face of the parts 64, 66. 35 During this movement, the grippers are stationary, the pins 178 being in the parallel portions 177 of the slots in the levers 170, 172. As the former 30 approaches its upper limit of movement, the roll 190 engages the cam 192, causing the toggle 188, 40 189 to be broken outwardly and pressure of the member 182 upon the former to be released. The parts now return to initial position and the machine stops with the 45 upper released.

Having thus described my invention, what I claim as new and desire to secure by Letters Patent of the United States is:

1. A machine of the class described having, in combination, means for confining the margin of the forepart of a shoe upper, a former projecting above the confining means and arranged for movement to engage the unconfined portion of the upper to stretch 50 it, and means movable relatively to the former prior to movement of the former for holding the upper at the end of the toe and causing it to be brought down over the end of the former without drawing back or fore- 55 shortening prior to its being engaged by the confining means so as to cause the upper to be humped over the former.

2. A machine of the class described having, in combination, means for confining the margin of the forepart of a shoe upper, a

former projecting above a confining face of the confining means and arranged to engage the unconfined portion of the upper to stretch it, and means arranged to receive the toe end of the upper substantially in the 70 plane of the top of the former and movable transversely of the upper for humping the upper over the former prior to the general engagement of the confining means with the upper. 75

3. A machine of the class described having, in combination, means for confining the margin of the forepart of a shoe upper, a former arranged to engage the unconfined portion of the upper to stretch it and to act 80 on the upper during movement of the confining means to confining position, and means operated by movement of the confining means toward upper confining position for seizing the upper at the toe end and 85 preventing rearward movement thereof during movement of the confining means into upper confining position.

4. In a machine of the class described, the combination with upper confining means, a 90 former, and means for relatively moving the confining means and the former, of means for effecting a longitudinal pull on the upper prior to the action of the confining means. 95

5. A machine for shaping uppers preliminary to lasting having, in combination, upper confining means, a former, means for moving the confining means and the former relatively, and means for exerting a longitudinal stretch upon the upper before the confining means becomes operative to confine the margin of the upper. 100

6. In a machine of the class described, the combination with upper confining means, a 105 former, and means for relatively moving the former and the confining means to shape the upper by withdrawing it from the confining means, of means on the confining means for first effecting a longitudinal stretching of 110 the upper.

7. In a machine of the class described, the combination with upper confining means, a former, and means for relatively moving the former and the confining means to shape the upper by withdrawing it from the confining means, of means for first effecting a stretching of the upper and then forming a part of the confining means during withdrawal of the upper from the confining 120 means.

8. In a machine of the class described, the combination with upper confining means, a former, and means for relatively moving the former and the confining means to shape 125 the upper by withdrawal of it from the confining means, of means arranged to extend beyond the upper engaging surface of the confining means in position to engage the upper first at the end of the toe and to be 130

depressed into the confining means and form a part thereof during the remainder of the upper forming operation.

9. In a machine of the class described, the combination of means for confining the margin of an upper, and a former about which the upper is shaped by relative movement of the former and the confining means, the confining means being constructed and arranged with yielding sections to engage and tension the upper prior to general engagement of the confining means with the upper margin.

10. A machine of the class described having, in combination, upper and lower confining members arranged to clamp between them the margin of the forepart of a shoe upper, and a toe former to be forced against the vamp so clamped, one of said clamping members having a separate toe clamping section resiliently held above the clamping surface of said member in position first to engage the upper at the end of the toe and arranged for depression by relative movement of the clamping members to permit the clamping members to effect clamping of the upper at the sides of the toe.

11. In a machine of the class described, the combination with upper confining means, a former, and means for relatively moving the confining means and the former to shape the upper, of a plurality of means for engaging the upper at the end of the toe and effecting a longitudinal pull on the upper before the upper is engaged by the confining means.

12. In a machine of the class described, the combination with upper confining means, a former, and means for relatively moving the confining means and the former to shape the upper, of a plurality of upper engaging members to hold the upper at the end of the toe, and spring means for pressing said members into engagement with the upper before it is clamped by the confining means.

13. In a machine of the class described, the combination with upper confining means, a former, and means for relatively moving the confining means and the former to shape the upper, of a plurality of upper engaging members to hold the upper at the end of the toe, said members being arranged both to hold the upper at first and to give up the upper successively as the upper is shaped.

14. In a machine of the class described, the combination with upper confining means, a former, and means for relatively moving the confining means and the former to shape the upper, of a plurality of upper engaging members to hold the upper at the end of the toe, and means for distributing yielding pressure between said members and causing each to engage the upper.

15. In a machine of the class described,

the combination with upper confining means, a former, and means for relatively moving the confining means and the former to shape the upper, of a plurality of upper engaging members to hold the upper at the end of the toe provided with differently formed upper engaging faces to hold the upper with different degrees of security.

16. In a machine of the class described, the combination with upper confining means, a former, and means for relatively moving the confining means and the former to shape the upper, of a plurality of upper engaging members to hold the upper at the end of the toe, and means for effecting and distributing unequally the upper holding pressure to said members.

17. A machine of the class described having, in combination, means for confining the margin of the forepart of a shoe upper, a former arranged to engage the unconfined portion of the upper to stretch it, and a plurality of yielding means on the confining means acting to effect a preliminary stretching of the upper longitudinally, the confining means having a rigid upper engaging portion located between the yielding means and adapted to engage the upper and confine it after yielding of the yielding means.

18. In a machine of the class described, the combination with upper confining means, a former, and means for relatively moving the confining means and the former to shape the upper, of means for effecting a pulling on the upper at a corner of the toe prior to the action of the confining means.

19. In a machine of the class described, the combination with upper confining means, a former, and means for relatively moving the former and the confining means to shape the upper by withdrawal of it from the confining means, of means yieldingly mounted in the confining means and arranged to extend beyond the upper engaging surface of the confining means in position to engage the upper first at the corners of the toe for pulling the upper radially of the curve of the toe prior to the action of the confining means.

20. In a machine of the class described, the combination with upper confining means, a former, and means for relatively moving the former and the confining means to shape the upper by withdrawal of it from the confining means, of means yieldingly mounted in the confining means and arranged to extend beyond the upper engaging surface of the confining means in position to engage the upper at the corners of the toe for pulling the upper radially of the curve of the toe and adjacent to the corners of the toe prior to the action of the confining means.

21. A machine of the class described hav-

ing, in combination, means for confining the margin of the forepart of a shoe upper, and a former arranged to engage the unconfined portion of the upper to stretch it, said upper confining means being constructed and arranged to operate during the action of said former first to engage the upper at the end of the toe, then to engage the upper at the corners of the toe, and finally to engage the upper continuously about the periphery of the toe.

22. A machine for shaping uppers preliminary to lasting having, in combination, upper confining means comprising members relatively movable to clamp the margin of an upper, a former, means for moving the confining means and the former relatively to cause the upper to be stretched over the former and drawn from the confining means, means operating prior to the confining means for effecting a longitudinal pull on the upper, and means for exerting a pull on the upper at the corners of the toe.

23. A machine for shaping uppers preliminary to lasting having, in combination, upper confining means comprising members relatively movable to clamp the margin of an upper, a former, means for moving the confining means and the former relatively to cause the upper to be stretched over the former and drawn from the confining means, means for effecting a longitudinal pull on the upper, and means acting subsequently to the longitudinal pull and prior to the remainder of the confining means to tension the upper at the corners of the toe.

24. A machine for shaping uppers preliminary to lasting having, in combination, upper confining means having sections successively operative to grip the upper first at the end of the toe, then at the corners of the toe, and finally about the entire toe, and a former between which and the confining means there is relative movement as the upper is thus successively gripped to tension the upper and wrap it about the former.

25. In a machine of the class described, the combination of relatively moving clamping members for confining the margin of a shoe upper acting first to confine the upper at the end and corners of the toe, then to seize the upper at the tip line, and later to confine the entire margin at the toe, and an inside former between which and the confining means there is relative movement to shape the upper and to cause the margin of the upper to be drawn through the confining means.

26. A machine of the class described having, in combination, means for clamping an upper marginally and along the tip seam, and a toe former to stretch the clamped upper, said machine being constructed and arranged first to clamp the upper locally at the end of the toe to effect a longitudinal strain

on the upper, and then locally at the corners of the toe to effect a stretching radially of the upper, and finally to clamp the upper continuously about the toe end.

27. In a machine of the class described, the combination with upper confining means, a former, and means for relatively moving the confining means and the former to shape the upper, of means for first effecting a pulling of the upper at the corners of the toe and then forming a part of the confining means during withdrawal of the upper from the confining means.

28. In a machine of the class described, the combination with upper confining means, a former, and means for relatively moving the former and the confining means to shape the upper by withdrawal of it from the confining means, of means yieldingly mounted in the confining means and arranged to extend beyond the upper engaging surface of the confining means in position to engage the upper at the corners of the toe and to be depressed into the confining means and form a part thereof during the remainder of the upper forming operation.

29. A machine of the class described having, in combination, means for confining the margin of the forepart of a shoe upper, a former arranged to engage the unconfined portion of the upper to stretch it, resilient means for engaging the upper at the end of the toe, separate resilient means for later engaging the upper at the corners of the toe, and rigid means on the confining means between the separate resilient means and the former for finally engaging the upper.

30. In a machine of the class described, the combination of relatively moving clamping members for confining the margin of a shoe upper, an inside former between which and the confining means there is relative movement to cause the margin of the upper to be drawn through the confining means, and supplemental gripping means for increasing the tension upon the upper at the corners of the toe.

31. In a machine of the class described, the combination of means for confining the margin of an upper with a former about which the upper is shaped by relative movement of the former and the confining means, the confining means being constructed with a ribbed surface and the rib having alternate rigid and yielding sections.

32. In a machine of the class described, the combination of means for confining the margin of an upper with a former about which the upper is shaped by relative movement of the former and the confining means, the confining means being constructed with a plurality of ribs which ribs have yielding sections interspersed with rigid sections.

33. A machine of the class described having, in combination, means for confining the

margin of the forepart of a shoe upper comprising upper and lower confining members, and a former arranged to engage the unconfined portion of the upper to stretch it, one 5 of said members having ribs arranged parallel with the contour of the toe and the ribs being more numerous about the end of the toe.

34. In a machine of the class described, 10 the combination of means for confining the margin of an upper with a former about which the upper is shaped by relative movement of the former and the confining means, the confining means being constructed with 15 a plurality of ribs which ribs have yielding sections interspersed with rigid sections, the rigid sections being arranged to break joints with the yielding sections.

35. A machine of the class described having, in combination, means for confining the 20 margin of the forepart of a shoe upper, a former arranged to engage the unconfined portion of the upper to stretch it, and three ribs on the confining means arranged in the 25 general direction of the contour of the former, the central rib being shorter than the other ribs and located at the end of the toe so that greater confining effect will be produced at the end of the toe than at the 30 sides of the toe.

36. A machine of the class described having, in combination, means for confining the margin of the forepart of a shoe upper, a former arranged to engage the unconfined 35 portion of the upper to stretch it, and ribs on the confining means arranged radially of the curve of the toe to distribute the fullness of the upper as it passes through the confining means in the upper forming 40 operation.

37. In a machine of the class described, the combination of relatively moving clamping members for confining the margin of a shoe upper, and an inside former 45 between which and the confining means there is relative movement to cause the margin of the upper to be drawn through the confining means, the portion of the confining means which engages the inner face of 50 the upper being provided with radial ribs to distribute and direct the folding and tensioning of the upper as it is drawn between the confining means.

38. A machine of the class described having, in combination, means for confining the 55 margin of the forepart of a shoe upper, a former arranged to engage the unconfined portion of the upper to stretch it, and a plurality of ribs arranged at each side of 60 the center of the toe to control the folds of upper fullness as the upper is drawn from between the confining means in the upper forming operation.

39. A machine of the class described having, in combination, means for confining

the margin of the forepart of a shoe upper, a toe former arranged to be forced against the upper to stretch it, mechanism for operating the confining means and the former, additional means for engaging the upper at 70 each side adjacent to the tip line, and means for effecting approaching movement of said additional means during the operation of the former.

40. A machine of the class described having, in combination, means for clamping the margin of the forepart of a shoe upper, a former movable relatively to the clamping means to stretch the upper, and means acting automatically to move the side edges of 80 the upper toward each other while the upper is held in clamped position.

41. A machine of the class described having, in combination, means for clamping the margin of the forepart of a shoe upper, a former movable relatively to the clamping means to stretch the upper, and means for moving the side edges of the upper toward 85 each other after the edges of the upper are clamped.

42. A machine of the class described having, in combination, means for clamping the margin of the forepart of a shoe upper, a former movable relatively to the clamping means to stretch the upper, operating means 95 for producing stretching movement, and means engaging the opposite margins of the upper near the tip seam constructed and arranged to be moved toward each other positively equal distances during the action of 100 the stretching means.

43. A machine for shaping shoe uppers preliminary to lasting having, in combination, an inside forepart former over which the forepart of an upper is to be 105 stretched, means co-operating with the inside former and movable relatively thereto for stretching the upper, an outside former constructed and arranged to engage the work over the tip seam, and cam actuated 110 means to move the outside former at a slower rate than the inside former to increase the holding pressure between the inside former and the outside former as the stretching progresses.

44. A machine of the class described having, in combination, means to confine the margin of the forepart of a shoe upper, means including an inside former operating to effect shaping of the unconfined portion 120 to the contour of the former and to effect drawing out and shaping of the margin into an upstanding flange, and means operated by closing movement of the confining means for gripping the upper margin at the sides 125 of the toe and feeding it laterally of the toe during the drawing out and shaping of the upper.

45. A machine of the class described having, in combination, means for clamping the 130

- margin of the forepart of a shoe upper, a toe former, means for effecting relative movement of said parts to cause clamping of the upper and stretching pressure of the former into the vamp, and means operating automatically for feeding the upper laterally at the tip seam during the action of the toe former. 5
46. A machine of the class described having, in combination, means for clamping the margin of the forepart of a shoe upper, a toe former, means for effecting relative movement of said parts to cause clamping of the upper and stretching pressure of the former into the vamp, and means operating automatically for feeding the upper laterally and toward the toe end during the action of the former. 10
47. In a machine of the class described, the combination of relatively moving clamping members for confining the margin of a shoe upper, an inside former between which and the confining means there is relative movement to cause the margin of the upper to be drawn through the confining means, supplemental means on the confining means for increasing the holding tension on the upper at the end and corners of the toe to draft the upper, and means arranged positively to engage the upper at the tip line and to feed the upper inwardly and forwardly as the upper is drawn from the confining means. 15
48. A machine of the class described having, in combination, means to confine the margin of the forepart of a shoe upper, means including an inside former operating to effect shaping of the unconfined portion to the contour of the former and to effect drawing out and shaping of the margin into an upstanding flange, and means for locally gripping the upper margin at the tip seam and feeding it obliquely toward the toe end of the former during the drawing out and shaping of the upper. 20
49. In a machine of the class described, the combination of relatively moving clamping members for confining the margin of a shoe upper, an inside former between which and the confining means there is relative movement to cause the margin of the upper to be drawn through the confining means, and grippers for controlling the formation of the upper at the tip line having toothed upper jaws and smooth lower jaws so that the upper leather will be held more firmly than the lining. 25
50. In a machine of the class described, the combination of relatively moving clamping members for confining the margin of a shoe upper, an inside former between which and the confining means there is relative movement to cause the margin of the upper to be drawn through the confining means, and supplemental jaws for holding the upper at the tip line having their gripping surfaces relatively formed to secure a firmer hold on the outside of the upper than on the inside. 30
51. A machine of the class described having, in combination, means for confining the margin of the forepart of a shoe upper, a forepart former, a tip seam clamp, operating mechanism constructed and arranged to cause the upper to be clamped between the former and the tip seam clamp and then between the upper confining means and thereafter to cause the former to shape the unconfined portion of the vamp, said operating mechanism for the tip seam clamp being constructed and arranged to tend to effect movement of the clamp at a less rate than the former is moved, and resilient means between the tip seam clamp and its operating means so that pressure on the tip seam increases as the forming operation proceeds. 35
52. A machine for shaping uppers having, in combination, means for confining the margin of an upper, a former, operating mechanism for effecting relative movement between said confining means and the former to shape the upper over the former, and means co-operating with the former to apply pressure to the upper comprising a power-driven element having a predetermined movement independently of the relative movement between the former and the confining means to control said pressure. 40
53. A machine for shaping uppers having, in combination, means for confining the margin of an upper, a former, operating mechanism for moving the former relatively to the confining means to shape the upper over the former, a member for engaging the upper and pressing it against the former, and controlling means for said member comprising mechanism movable relatively to the former to apply increased pressure to the upper through said member in the movement of the former. 45
54. A machine for shaping shoe uppers preliminary to lasting having, in combination, an inside forepart former over which the forepart of the upper is to be stretched, means co-operating with the inside former for stretching the upper when the inside former is moved, an outside former constructed and arranged to engage the work over the tip seam and to move with the inside former, and actuating means for the outside former arranged to move at a slower rate than the inside former so that the holding pressure between the inside former and the outside former increases as the stretching progresses. 50
55. A machine for shaping shoe uppers preliminary to lasting having, in combination, an inside forepart former over which the forepart of an upper is to be stretched, means co-operating with the inside former 55

for stretching the upper when the inside former is moved, an outside former constructed and arranged to engage the work over the top of the toe adjacent to the tip seam, and actuating means for the outside former including a yielding element and constructed and arranged to move at a slower rate than the inside former so that the pressure of the outside former upon the tip seam increases with the stretching tension.

56. A machine of the class described having, in combination, an open plate, a co-operating member adapted to confine the margin of the forepart of a shoe upper upon the plate, a toe former normally occupying positions projecting partially over the open plate to cause the vamp to be humped over said former when it is confined, means for holding the upper against withdrawal from the confining member while it is being confined, means for operating the confining member to confine the upper, means for operating the former for withdrawing the upper from the confining means, and means for forcing the upper against the former to hold the upper about the former after it is withdrawn from the confining means.

57. A machine for shaping shoe uppers preparatory to lasting having, in combination, means for seizing and pulling the margin of an upper, a forepart former, operating mechanism for producing upper shaping movement between the former and the margin holding means, a device co-operating with the forepart former to press the upper upon the former and constructed and arranged to press upon the toe in the region of the tip line, and means for automatically releasing the device and moving it away when the shaping operation is completed.

58. A machine for shaping shoe uppers preliminary to lasting having, in combination, means for holding an upper margin, an inside former for stretching the upper, an outside compressing member engaging the upper over the tip line, means to operate the inside former to draw the margin from the margin holding means, and to move the compressing member with the inside former, means to stop the machine with the stock under tension and compression by the compressing member, means operating when the machine has restarted to release the compressing member and move it away from the inside former, and means for further actuating the inside former to withdraw the upper from the holding means and bend it into an upstanding flange.

59. A machine for shaping shoe uppers preliminary to lasting having, in combination, means for holding an upper margin, an inside former for stretching the upper, an outside compressing member engaging the upper over the tip line, means to oper-

ate the inside former to draw the margin from the margin holding means, means to move the compressing member with the inside former, means to stop the machine with the stock under tension and compression by the compressing member, means operating when the machine has restarted automatically to release the compressing member and move it away from the inside former, and means for further actuating the inside former to withdraw the upper from the holding means and bend it into an upstanding flange.

60. In a machine of the class described, the combination of upper confining means, a former, means for relatively moving the confining means and the former to withdraw the upper from the confining means and form it into a flange perpendicular to the bottom of the former, means for holding the upper clamped to the former about the end and sides of the former, and means for stopping the machine with the upper so held to allow it to set to the shape into which it has been formed, said holding means acting when the machine is restarted to iron the upper at the end and sides of the former toward the bottom of the former.

61. In a machine of the class described, the combination of upper confining means, a former, means for relatively moving the confining means and the former to withdraw the upper from the confining means, and means acting during the relative movement of the former and the confining means to iron the upper at the sides of the former toward the rear of the former.

62. In a machine of the class described, the combination of upper confining means, a former, means for relatively moving the confining means and the former to withdraw the upper from the confining means, and means acting during a part of the relative movement of the former and the confining means to press the upper at the end of the toe against the former and acting continuously to press the upper against the sides of the former.

63. In a machine of the class described, the combination of upper confining means, a former, means for relatively moving the confining means and the former to withdraw the upper from the confining means, and means acting during the relative movement of the former and the confining means to press the upper at the end and sides of the toe against the end and sides of the former, the side pressure being effected independently of the end pressure.

64. In a machine of the class described, the combination of upper confining means, a former, means for relatively moving the confining means and the former partially to withdraw the upper from the confining means, and means engaging the inner side

of the upper against which the upper may be held by the operator to prevent movement of the upper toward the confining means.

5 65. In a machine of the class described, the combination of upper confining means, a former, means for relatively moving the confining means and the former partially to withdraw the upper from the confining means, and a series of teeth projecting above the surface of the former to engage the inner side of the upper when the upper is pressed against it by the operator and prevent the upper from being drawn forwardly 10 during the operation of forming the upper.

66. In a machine for shaping uppers off the last, the combination with a former over which to shape the toe end portion of an upper, of means for wiping the upper over 20 the upper shaping surface of the former between the bottom and the top of the former, and means for engaging the top of the forepart of the upper and pressing it against the former as the upper is wiped 25 over the former.

67. In a machine for shaping uppers off the last, the combination with a former over which to shape the toe end portion of an upper, of means for wiping the upper over 30 the upper shaping surface of the former in the direction of the height of the former, a clamp member for engaging the upper and pressing it against the former, and means automatically operative to increase the clamping pressure of said member on the upper as the wiping operation 35 proceeds.

68. In a machine for shaping uppers off the last, the combination with a former over 40 which to shape the toe end portion of an upper, of means for embracing the upper about the former and wiping it heightwise of the former over the upper shaping surface of the former, operating means for 45 moving the former relatively to said wiping means to wipe the upper, and a spring controlled member movable with the former and arranged to engage the top of the forepart of the upper and press it against the 50 former in the wiping operation.

69. In a machine for shaping uppers off the last, the combination with a former over which to shape the toe end portion of an upper, of means for clamping the marginal 55 portion of the upper round the toe, operating means for effecting relative movement of the clamping means and the former to draw the upper over the former, additional means automatically operative in such relative movement of the clamping means and the former to wipe the upper heightwise of the former over the upper shaping surface of the former, and means for engaging the upper and pressing it against the former to

assist in holding the upper against displacement as the upper is shaped over the former. 65

70. In a machine for shaping uppers off the last, the combination with a former over which to shape the toe end portion of an upper, of means for clamping the marginal 70 portion of the upper round the toe, operating means for moving the former relatively to said clamping means to draw the upper over the former, additional means automatically operative in such movement of 75 the former to wipe the upper over the upper shaping surface of the former, and a member movable with the former and arranged to engage the top of the forepart of the upper and press it against the former as the 80 upper is shaped over the former.

71. In a machine for shaping the end of a shoe upper off the last into the form it is to have in the finished shoe, the combination of a former, means for confining marginal portions of the upper with the upper 85 in operative relation to the former, means for relatively moving the former and the confining means heightwise of the former to lay the upper about the former, and 90 means automatically conformable to the shape of the former for working the upper heightwise of the former by pressure applied to the upper about the end of the former as the upper is being laid about 95 the former.

72. In a machine for shaping the end of a shoe upper off the last, the combination of a former having the shape the upper is to assume, means for supporting the shoe 100 upper with the end portion in operative relation to the former, means for relatively moving the former and the supporting means to lay the upper about the former, and yielding end embracing means acting 105 to conform the upper to the shape prescribed by the former and to work the upper heightwise of the former by pressure applied to the upper about the end of the former as the former and supporting means 110 are moved relatively.

73. In a machine for shaping uppers, the combination of means for seizing the margin of an upper, a forepart former, means for effecting relative positive movement between the seizing means and the former to shape the upper, means for clamping the upper against the former including resilient means, and additional means operated in conjunction with the relative movement of the seizing means and former for varying the compression of the resilient means during the forming operation to control the pressure of the clamping means upon the work. 115

74. In a machine of the class described, the combination of means for confining the margin of the forepart of a shoe vamp, a 120 125

vamp former arranged for movement relatively to the confining means to engage the unconfined portion of the vamp and shape it, a clamp to hold the upper against the former during movement of the former and movable therewith, a spring acting to hold the clamp against the former, and connec-

tions for automatically controlling the tension of the spring during movement of the former.

10

In testimony whereof I have signed my name to this specification.

MATTHIAS BROCK.
